Patented July 22, 1975

236,034

MYRINGATOME-ASPIRATOR-TUBE INSERTER

James L. Geraci, Cincinnati, Ohio, assignor to
Xomox Corporation

Filed Sept. 18, 1973, Ser. No. 398,510

Term of patent 14 years

Int. Cl. D24—02

U.S. Cl. D83—12 R

FIG-1

FIG-2

FIG-3

FIG-4

FIG-5

FIG-6

FIG. 1 is a perspective view of a myringatome-aspirator-tube inserter of my new design showing the upper, front, and left side thereof.

FIG. 2 is a top plan view thereof.

FIG. 3 is a side view illustrating the left side thereof.

FIG. 4 is a front view thereof.

FIG. 5 is a rear view thereof.

FIG. 6 is a bottom plan view thereof.

I claim:

The ornamental design for a myringatome-aspirator-tube inserter, as shown.
